CLAIM

The ornamental design for a golf push trolley, as shown and described.

DESCRIPTION

FIG. 1 is a front elevational view of a golf push trolley showing our new design;

FIG. 2 is a rear elevational view thereof;

FIG. 3 is a right side view thereof;

FIG. 4 is a left side view thereof;

FIG. 5 is a top plan view thereof;

FIG. 6 is a bottom plan view thereof;

FIG. 7 is a first perspective view thereof;

FIG. 8 is a second perspective view thereof;

FIG. 9 is a third perspective view thereof;

FIG. 10 is a front elevational view of a golf push trolley in a folded state;

FIG. 11 is a rear elevational view of FIG. 10;

FIG. 12 is a right side view of FIG. 10;

FIG. 13 is a left side view of FIG. 10;

FIG. 14 is a top plan view of FIG. 10;

FIG. 15 is a bottom plan view of FIG. 10;

FIG. 16 is a first perspective view of FIG. 10;

FIG. 17 is a second perspective view of FIG. 10; and,

FIG. 18 is a third perspective view of FIG. 10.

1 Claim, 18 Drawing Sheets
